UNITED STATES PATENT OFFICE.

ROBERT G. DEXTER AND SAMUEL S. AUCHINCLOSS, JR., OF BOSTON, MASSACHUSETTS.

SPOTLIGHT.

Application filed January 22, 1925. Serial No. 4,104.

This invention relates to a spotlight or auxiliary headlight for motor vehicles and the like and has for its object to provide for a foot operated and controlled light, 5 movable both in a horizontal and a vertical plane, whereby maximum illumination is obtained for night driving.

One of the objects of our invention is to construct and mount an auxiliary light, 10 preferably at the lower, left hand corner of the radiator of a motor vehicle at a point below the normal line of vision including foot controlled mechanism for shifting the light in a plurality of positions in a horizontal plane so that the operator of the 15 machine may guard against the side of the road as well as the traffic moving in the opposite direction.

Another object of our invention is to provide a headlight of the above character and 20 description, which may be adjusted in a vertical plane so that the operator may project the light at any desired distance in advance of the machine, yet permitting free 25 lateral movement or movement from the left to the right from a position at the steering wheel without removing the hands or detract from the proper driving of the vehicle.

To enable others skilled in the art to fully 30 comprehend the underlying features of our invention that they may embody the same in the various modifications in structure and relation contemplated, drawings depicting a preferred form have been annexed as a part 35 of this disclosure and in such drawings, similar reference characters denote corresponding parts throughout all the views, of which,

Figure 1 is a side view showing the spotlight or headlight mounted at the front of the machine.

Figure 2 is a plan showing the different lateral positions of the light.

Figure 3 is an enlarged side view of the bracket, the supporting casting being shown 45 in section.

Figure 4 is a sectional view taken on the line 4-4 of Figure 3.

Figure 5 is a front view of the rocker 50 pedal.

Figure 6 is a sectional view taken on the line 6-6 of Figure 5.

Referring now to the drawings wherein like reference characters designate corresponding parts throughout the several views,

5 designates the front of the conventional type of motor vehicle and 6 the dash and instrument board. Mounted at the front of the radiator and preferably to the lower, left hand side thereof is an attaching plate 60 7 having apertures 8, 9, at the top and bottom for the reception of screws or other fastening elements whereby the plate may be permanently secured to the radiator. The plate supports a casting designated 65 in its entirety by numeral 10 having a flared, outer flange 11 for engagement with the plate 7 above referred to. The casting 10 is for the most part hollow so as to reduce its weight, having a head 12 substantially 70 square in cross section. The head is split as indicated at 13 and is further provided with a threaded screw 14 tapped therein so as to properly confine the gearing subsequently to be referred to.

75 Referring particularly to Figures 3 and 4, it will be observed that there is provided a longitudinal slot or groove 15 in one side of the head, said groove communicating with a machined or milled out chamber or housing 16 for receiving the bracket and spindle of the spotlight or lamp proper. Within the groove or slot 15 is a rack 17 and rod 18 attached thereto, said rod receiving a coil spring 19. One end of the spring bears 80 against the rack 17 and the opposite end of the spring against a threaded screw 20, threaded in the side of the casting. A cable 21 within a cable housing 22 is connected to the rod 18, said cable extending rearwardly 85 through a floor plate 23 and attached to the bottom and preferably to the right side of a rocker pedal 24 as by a screw 25 or other fastening means. A rocker pedal is formed with vertical extensions 26 which straddles the flange 27 of the floor plate 23 and pivoted thereto as at 28 so that the operator may rock the rocker pedal to actuate the rack bar 17 for the purpose subsequently to be referred to.

100 The rack bar 17 meshes with a pinion 30 keyed on a short vertical shaft 31 extending within the head 12. A collar 32 is fastened to the shaft so as to retain the pinion in proper position. A screw head 33 is fastened to the lower end of the shaft 31 between the screw head and collar, ball bearings 34 are provided in a raceway and additional ball bearings 35 between the pinion and a top plate 36 permitting free rotation of 110

the shaft 31 in a horizontal plane when actuated by the rack bar 17 when the rocker pedal is depressed toward the left, for instance.

5 The upper end of the shaft 31 supports the bracket 37, fastened thereto by an adjusting nut bolt 38 whereby the socket 39 and lamp shade 40 may be adjusted vertically. The cables or leads from the socket 39 are 10 provided and connected to a suitable source of current such as a battery 40^a.

Under normal conditions, tension on the spring 18 will force the rack bar 17 outwardly so that the lamp shade and lamp 40 will be turned toward the right side of the machine. If pressure, therefore, is exerted 15 on the rocker pedal so as to actuate it and move the pedal on its pivot toward the left, tension will be created on the cable and the 20 rack bar and meshing pinion will be actuated to rotate the shaft 31 first toward the center and to the left of the vehicle. Of course, when pressure is released from the 25 rocker pedal, it will return to its normal horizontal position as shown by Figure 5 and the lamp shade 40 will be directed toward the right of the machine and to the 30 side of the roadway. The entire device and particularly the lamp shade 40 is mounted 35 at a point below the normal line of vision of the operator so as to not to interfere with the regular headlights of the machine. The operator may actuate the headlight by the 40 foot without removing his hands from the steering wheel, which is very important in careful driving.

While we have illustrated and described our invention with some degree of particularity, we realize that in practice various alterations therein may be made. We 40 therefore reserve the right and privilege of changing the form of the details of construction or otherwise altering the arrangement

of the correlated parts without departing from the spirit of the invention or the scope 45 of the appended claims.

Having thus described our invention, what we claim as new and desire to secure by United States Letters Patent is:—

1. A spotlight for motor vehicles and the 50 like comprising a lamp supporting bracket, a vertical shaft, a horizontal pivot supporting the bracket on said shaft, a casting, means for attaching said casting to the front of a motor vehicle, a pinion located on the 55 lower end of the shaft and located within the said casting, a spring controlled rack bar meshing with the pinion and slidable in said casting, a cable connected to said rack bar, a rocker pedal for actuating said cable and gearing whereby the lamp supporting bracket is rotated in a horizontal plane, and means for adjusting the rack bar relatively to said pinion to take up wear.

2. A spotlight for motor vehicles and the 60 like comprising a lamp supporting bracket, a shaft, a horizontal connecting pivot for said bracket and shaft, a hollow casting, means for attaching said casting to the front of a motor vehicle, a pinion and ball bearings located within the casting on the lower 65 end of the shaft, a longitudinal groove within the casting, means for closing said groove, a rack bar within said groove, a spring 70 associated therewith for normally retracting said bar, said bar meshing with the pinion, a rocker pedal and a cable connecting the 75 said rack bar with the rocker pedal, a threaded member for drawing the parts of the casting together whereby the rack and the 80 pinion may be adjusted relatively to each other.

In testimony whereof we affix our signatures.

ROBERT G. DEXTER. [L. S.]
S. S. AUCHINCLOSS, JR. [L. S.]
